(57) **CLAIM**

I claim the ornamental design for a kinked O-ring, as shown and described.

DESCRIPTION

FIG. 1 is an isometric view of my design for a kinked O-ring; FIG. 2 is a front view of the design for the kinked O-ring shown in FIG. 1, the rear view being identical; and, FIG. 3 is a top view of the design for the kinked O-ring shown in FIG. 1, the bottom view and both left and right side views being identical.

1 Claim, 2 Drawing Sheets***FIG. 1***

FIG. 3
